PRINTING MACHINE

Welling L. Parmele and Howard W. Parmele,
Chicago, Ill., assignors to Naz-Dar Company,
Chicago, Ill., a corporation of Illinois

Application May 21, 1932, Serial No. 612,722

25 Claims. (Cl. 101—123)

This invention relates to an improved machine for printing or stenciling designs on cardboard, or other sheet material, by the use of inks or paints which are applied to the sheet through a silk stencil, or other suitable screen, the paint being applied by the use of a squeegee which is moved over the stencil to rub the paint through the penetrable areas of the stencil onto the underlying sheet.

10 In machines of this class there is usually provided a bed plate, upon which the sheet rests during the interval of printing, and in combination therewith a printing or stencil-supporting frame which is arranged to be moved to and from printing position on the bed plate. The squeegee is supported in the printing frame, being arranged for movement therein over the stencil. Ordinarily means is also provided for supplying fresh sheets to the bed plate, and for removing the printed sheets therefrom.

15 One of the important objects of the present invention is to provide in a machine of this class improved means for operating the squeegee in a manner which will prevent accumulation of paint on the stencil in front of the squeegee at the end of the active stroke of the latter.

20 Another object of the invention is to provide an improved sheet conveyor means, and control mechanism therefor, which will operate to position a fresh sheet on the bed plate in accurate registration with the stencil.

25 Another object of the invention is to provide means for adjusting the position of the printing frame relative to the bed plate, whereby to accommodate the machine to the printing of sheets of various thicknesses.

Another object of the invention is to provide means for mounting the printing frame on the bed plate base in a manner to permit limited vertical movement of said frame relative to the bed plate and also to permit tilting of the frame about one side to semi-vertical position.

Another object of the invention is to provide means for automatically supplying paint in regulated amount to the face of the stencil.

A further object of the invention is to provide a manually-controlled safety device for preventing movement of the printing frame to printing position on the bed plate.

50 A still further object of the invention is to provide manually-controlled means for rendering the squeegee drive mechanism inoperative in the event of an emergency such as a failure of the sheet feed means.

55 Other objects and advantages of the invention

will be apparent from the following detailed description, which, taken in connection with the accompanying drawings, discloses a preferred embodiment thereof.

Referring to the drawings:

Fig. 1 is a side elevational view of the machine showing the general relationship between the bed plate, the printing frame, the feed table, and the discharge platform;

Fig. 2 is a top plan view showing the printing frame and adjacent portions of the feed table and the discharge platform;

Fig. 3 is an end elevational view of the machine as viewed from the right in Fig. 1;

Fig. 4 is a fragmentary elevational view of a portion of the back of the machine showing parts of the squeegee drive mechanism;

Fig. 5 is a transverse section through the machine taken on line 5—5 of Fig. 4;

Fig. 6 is a detail section showing a portion of the gear train for driving the sheet conveyor, the view being taken on line 6—6 of Fig. 1;

Fig. 7 is a fragmentary elevational view showing a portion of the gear mechanism for driving the sheet conveyor;

Fig. 8 is a horizontal section taken on line 8—8 of Fig. 7;

Fig. 9 is a longitudinal section through the bed plate and printing frame, the view being taken on line 9—9 of Fig. 2;

Fig. 9a is a partial side elevational view of the automatic paint feed means;

Fig. 10 is a detail section showing the means for operating the clamp mechanism of the sheet gripper bars, the view being taken on line 10—10 of Fig. 2;

Fig. 11 is a horizontal section taken on line 11—11 of Fig. 10;

Fig. 12 is a detail section through one end of the printing frame taken on line 12—12 of Fig. 2, the view showing the means for controlling movement of the squeegee at the end of the advance stroke;

Fig. 13 is a top plan view of the mechanism shown in Fig. 12;

Fig. 14 is a section taken on line 14—14 of Fig. 13;

Fig. 15 is a top plan view of an edge portion of the printing frame and the bed plate, the view showing the safety mechanism for preventing movement of the printing frame onto the bed plate;

Fig. 16 is a fragmentary section through a portion of the discharge platform showing the

means for releasing the gripper bars from the sheet;

Fig. 17 is a section through the gripper bar release mechanism taken on line 17—17 of Fig. 16; 5 and

Fig. 18 is a detail plan view showing the connection between the end of one of the gripper bars and the associated conveyor chain.

Referring to the general views of the machine shown in Figs. 1 to 3, and Fig. 5, the numerals 10 21 and 22 indicate front and back side frame members supported on vertical posts 23 and tied together by cross-bars 24 and 25. A bed plate 26 is supported in horizontal position on members 15 21 and 22 by a frame piece 27, the latter consisting of spaced side members 28 and 29 which are supported, respectively, upon frame members 21 and 22. The side members 28 and 29 are tied together by heavy cross pieces 31, which are formed 20 as an integral part of bed 26, the ends of said members 31 being connected to side members 28 and 29 by key strips 32. A printing frame is disposed over bed plate 26 and is adapted to be raised and lowered relative to the latter by mechanism 25 later to be described. This frame is rectangular in shape and consists of side members 33 and 34, and end members 35 and 36, these members being preferably formed integrally with one another to provide a rigid frame unit. The printing frame 30 is adjustably supported on the base frame at its four corners by roller devices indicated generally by the numeral 20, the construction of which will be later described. A stencil 30 mounted in the printing frame is arranged for movement with 35 the latter to and from printing position on the bed plate in a manner which will hereinafter more fully appear.

Referring to Figs. 3—5, the printing frame is arranged for limited vertical movement relative 40 to the bed plate to allow sheets to be fed onto and removed from the bed, and is also arranged to be pivoted about one of its sides into semi-vertical position in order to facilitate removal of the stencil and to give free access to the bed plate. To 45 this end there is provided a pivotal and sliding connection between the printing frame and the base which connection comprises a bracket 37 which is bolted to frame member 21, and a second bracket 38 carried by member 33 of the printing 50 frame. Brackets 37 and 38 are interconnected by means of a rod 39 which is journaled at its opposite ends in bracket 37 and the central portion of which engages a U-shaped bearing piece 41 which forms a part of bracket 38. The printing 55 frame is tilted to and from vertical position by means of a cable 42 which is secured at one end to a cross piece 43 carried by the printing frame, the other end of said cable being wound on a drum 44 which is journaled in the upper free 60 end of an arm 45 which is secured through bracket 37 to the base. The shaft of drum 44 is provided with a worm wheel 46 which meshes with a worm 47, the latter being turned by a hand-wheel 48. By turning wheel 48 in the proper direction, cable 42 is wound up on drum 44, thereby 65 tilting the printing frame upwardly to the dotted line position shown in Fig. 3. Reverse movement of wheel 48 effects lowering of the printing frame back into normal printing position on the 70 bed plate.

As shown in Figs. 1 and 2, a feed table 49 is supported adjacent one end of the bed plate by a pair of frame pieces 51 which are secured to and form continuations of side frame members 21 and 75 22. A base plate 52, extending transversely of

the machine between frame pieces 51, affords a rigid support for table 49. A discharge platform 53 provided on its side edges with guide rails 54 is mounted adjacent the other end of the bed plate in position to receive the printed sheets as they are removed from the latter. Platform 53 is supported upon a pair of side frame pieces 55, the latter being tied to the main portion of the frame by brace arms 56. The outer ends of frame pieces 55 are supported by legs 57 which depend from side frame brackets 58.

Referring to Figs. 1 and 10, conveyor means is provided for feeding sheets from table 49 onto bed plate 26 and for removing the printed sheets from said plate onto discharge platform 53. In the embodiment shown this conveyor mechanism comprises a pair of endless chains 59 which are mounted on the opposite sides of the machine and which are provided at regularly spaced intervals with a series of gripper bars 61 (Fig. 10) which extend across the chains and which are secured at their ends to the links of the chains. These chains 59 pass upwardly between feed table 49 and the adjacent edge of the bed plate around a pair of sprockets 62 which are secured to a shaft 63, said shaft being journaled at its opposite ends in brackets 51. From sprockets 62 the conveyor chains extend along the opposite sides of bed plate 26, the chains during this portion of their run being supported in guide channels 64 (Fig. 5) which are formed in the upper edges of base frame members 28 and 29. The horizontal stretch of the chains continues from the bed plate over the top of discharge platform 53, from which point the chains pass downwardly around sprockets 65 which are carried on a shaft extending between frame brackets 58. From this point the chains pass under a pair of take-up sprockets 66 which are carried on stub shafts 67, thence over a pair of idler sprockets 68 which are mounted for free 115 rotation on a shaft 69, thence under a pair of drive sprockets 71 which are fixedly secured on a shaft 72, and finally back to sprockets 62. Shafts 67, which carry take-up sprockets 66, are journaled in arms 73, the latter being suspended from 120 the frame on a shaft 74. Arms 73 are provided with clamps 75 which permit of their adjustment on shaft 74, thereby permitting a setting of sprockets 66 to take up for slack in the chains.

The construction of the gripper bars is best 125 shown in Figs. 10, 16, and 18. These bars are all of similar construction and hence will be described in the singular. Each bar comprises: a blade 76 which extends between the conveyor chains; end plates 77 fixedly secured to the opposite ends of blade 76 and provided on their lower edges with rollers 78; blocks 79 for connecting the ends of blade 76 to the links of the carrier chains; a clamping jaw, indicated generally by the numeral 81, and consisting of a series of bars 130 or hold-down fingers 83 which are rigidly secured to a rock shaft 82 (Fig. 2); and arms 84 rigidly secured to the ends of shaft 82.

End plates 77 are cut away to provide a recessed portion 85 (Fig. 17) in which are mounted 140 latch levers 86, said levers being carried on pins 87 which are journaled in the wall portions of the end plates. Levers 86 are of bell-crank shape, the short arms 88 thereof being provided with lateral projections 89 which are urged toward 145 arms 84 by coil springs 91, the latter being contained in a recess formed in end plates 77. In Figs. 16 and 17 clamp jaw 81 is shown in the un-clamped position, in which position arms 84 are out of engagement with latch levers 86. When 150

said arms 84 are thrown upwardly, by means presently to be described, levers 86 are pivoted in a clockwise direction, viewing Fig. 17, thereby throwing projections 89 underneath arms 84 to hold the latter, together with jaw 81, in clamped position. The free edge of jaw 81 is provided with spaced prongs 92 which bite into the edge of the sheet to firmly hold it against blade 76.

The means which is provided for driving shaft 72 to move the conveyor chains a distance sufficient to position a fresh sheet below the printing frame will now be described. Referring to Figs. 1, and 6-8, this drive mechanism comprises: a motor 93 which is mounted on a cross-bar 94 carried by the frame; a sprocket 95 mounted for free rotation on a stub shaft 96 and adapted to be driven from the armature of motor 93 through a chain 97 which takes over a sprocket 98 secured to said armature shaft; a spur wheel 99 secured to the hub of sprocket 95 and positioned in permanent driving engagement with a second spur wheel 101 which is fixedly secured to a stub shaft 102, the latter being provided at its outer end with a hand wheel 103; a spur wheel 104 fixedly secured to a cross shaft 105 and positioned in driving engagement with a spur gear 100 carried on shaft 102; a disc 106 fixedly secured to the front end of shaft 105; a crank 107 eccentrically connected through a pin 108 to disc 106; a drive segment 109 rotatably supported on a stub shaft 111 and pivotally connected through a pin 112 to crank 107; a drive disc 113 fixedly secured to shaft 111 and provided on its periphery with three equally spaced shouldered notches 114 adapted to be engaged by a pawl 115 carried by drive segment 109; and means providing a drive connection between shaft 111 and sprocket drive shaft 72, said last-mentioned means including a gear train consisting of a spur wheel 116 fixedly secured to a stub shaft 117 and positioned to mesh with a spur gear 118 carried by shaft 72, and a spur gear 119 carried by the hub of wheel 116 and adapted to be driven from shaft 111 through a spur wheel 121 carried by said shaft 111.

Motor 93 is arranged to operate in such direction that it drives crank disc 106 in a counter-clockwise direction, viewing Figs. 1 and 7. Continuous rotation of disc 106 causes crank 107 to produce oscillatory movement of drive segment 109. In the position of the parts shown in Fig. 7, the crank has completed its stroke and drive disc 113 has completed its rotation through 120° under the action of segment 109 and pawl 115. Upon movement of crank 107 to the left, viewing Fig. 7, drive segment 109 will be turned in a clockwise direction on shaft 111 until pawl 115 engages in the succeeding one of the notches 114, this engagement being effected by a U-shaped leaf spring 121 which is carried by pin 112 and which bears against said pawl. Upon the return stroke of crank 107, drive segment 109 will turn disc 113 in a counter-clockwise direction through 120°, which movement is imparted to sprocket chain drive shaft 72 through gear train 121, 119, 116, and 118. This last-mentioned group of gears is such that a turning of shaft 111 through 120° will rotate the chain drive sprockets 71 a distance sufficient to move the conveyor chains the exact amount necessary to remove a printed sheet from the bed plate and to replace it by a fresh sheet.

A stop device is provided for insuring that the conveyor chains will stop at exactly the point which will bring the fresh sheet into printing position. This mechanism, which is shown in

Figs. 7 and 8, comprises a latch arm 122 pivoted at 123 to the frame and provided at its free end with a roller 124 which is adapted to be received in V-shaped notches 125 formed in the rim of disc 113. Roller 124 is yieldingly pressed against the rim of disc 113 by a coil spring 126 which is disposed about the shank of bolt 127, said bolt being carried by lever 122 and having sliding engagement with a lug 128 on the frame which serves as a stop for one end of spring 126, the other end of said spring bearing against arm 122. The V-shaped notches 125 are spaced on disc 113 at intervals of 120° to correspond exactly to the spacing of drive notches 114, and arm 122 is so positioned that roller 124 will be seated against one of the notches 125 at exactly the point at which segment 109 completes advance movement of drive disc 113. The conveyor chains are thus brought to a positive stop at exactly the right time to insure the positioning of the sheet in proper position on the bed plate. Additional means for further insuring accurate registration of the sheet with respect to the printing frame and stencil will be presently described.

The printing frame is arranged to be raised and lowered on the bed plate in time sequence with the sheet feed means. Referring particularly to Figs. 2 and 4, a pair of guide rails 129 and 130 are secured to the bed plate supporting frame 28 and 29 adjacent the opposite ends of the printing frame. These guide rails are arranged to support corresponding pairs of reciprocating cam blocks 131 and 132, there being provided a tongue and groove connection between the guide rails and their associated cam blocks as indicated at 133 (Fig. 5). The lower edge of each of the blocks 131 and 132 is toothed as indicated at 134, and the upper edge of each of said blocks is provided with an upwardly sloping cam surface 135 which terminates at its upper end in a comparatively short flat surface portion 136, the lower end of inclined surface 135 terminating in a comparatively long flat surface portion 137. The printing frame is provided at each corner with a roller 138 which is journaled in the lower end of a block 139, said block being supported for vertical sliding movement between a pair of guide rails 141 and 142 which are secured to the side members of the printing frame. Blocks 139 are normally held in fixed position between rails 141 and 142 by levers 143 which are pivoted at 144 to the side of the printing frame. The ends 145 of each pair of levers 143 at the opposite ends of the frame are held down by a cross-bar 146 (Fig. 3) which is supported from the end wall 130 of the frame by a guide rail 147, the latter being secured to the frame and having tongue and groove connection with a strip 148 which is carried by bar 146. The opposite ends of bar 146 are provided with downwardly extending cam projections 149 (Fig. 3) having cam surfaces 151 for engaging against the ends of levers 143. The movement of bar 146 is effected by means of a worm 152 carried by a shaft 153 which is journaled in a bracket 154 carried by the end wall of 140 the printing frame. Worm 152 meshes with a toothed rack 155 which is formed on bar 146. A hand wheel 156 secured to the outer end of shaft 153 provides means for turning the latter together with worm 152 to effect either forward or backward movement of bar 146. Movement of bar 146 toward the right, viewing Fig. 3, will depress levers 143, which in turn push blocks 139 and rollers 138 downwardly relative to the printing frame, thereby raising the latter relative to 150

cam blocks 131 and 132. The lower limiting position of the printing frame relative to the bed plate is thus readily adjusted to accommodate the machine to the printing of stock of various thicknesses. Coil springs 157 (Fig. 4) extending between blocks 139 and a fixed point on rails 142, serve to hold said blocks in yielding engagement with levers 143.

Referring to Figs. 1, 4, and 5, cam bars 131 are reciprocated in their associated guide supports 128 by a pair of toothed segment gears 158 which are fixedly secured to shaft 69. The teeth of segment gears 158 mesh with the teeth 134 extending along the under sides of bars 131. Similarly cam bars 132 are reciprocated in their associated guides 129 by a pair of toothed segment gears 159 which are rigidly secured to a shaft 160 which extends transversely of the frame. The teeth on segment gears 159 mesh with the teeth 134 on the under surfaces of the blocks 132. It will be apparent that turning of segment gears 158 in a counter-clockwise direction, viewing Fig. 1, will slide cam bars 131 to the left to cause rollers 138 to ride up the inclined surfaces 135 on said bars, thereby raising the end of the printing frame. A clockwise movement of segment gears 158 will move bars 131 to the right, viewing Fig. 1, to lower the end of the printing frame. The operation of segment gears 159 at the other end of the frame is similar. Turning of said gears in a clockwise direction, viewing Fig. 1, draws blocks 132 to the right to raise the frame, and movement of said gears in a counter-clockwise direction moves blocks 132 to the left to lower the frame.

Shafts 69 and 160 which carry segment gears 158 and 159, respectively, are driven in timed relation to the feed means from shaft 105 which, it will be recalled, is also used to drive the conveyor chains. Referring particularly to Figs. 1 and 5, shaft 105 carries a spur gear 161 which meshes with a spur wheel 162 carried by a stud shaft 163, said gear wheel 162 in turn meshing with a spur gear 164 which is carried by the hub 45 of a crank disc 165, said gear 164 and disc 165 being journaled for free rotation on a stub shaft 166. Crank disc 165 connects with shaft 160 through a link 167 which connects at one end with an eccentric pin 168 carried by disc 165, the other end of said link 167 having pivotal connection with an arm 169, the latter being rigidly secured to shaft 160. Disc 165 is driven in a clockwise direction, viewing Fig. 1, and for each complete revolution produces one complete oscillatory movement of segment gears 159. Segment gears 158 are similarly driven from shaft 105 through a train of gears 171, 172, and 173 (Fig. 5), the latter being secured to the hub of a second crank disc 174. Shaft 69 connects with crank disc 174 through a crank 175, the latter connecting at one end with an eccentric stud 176 carried by disc 174, the other end of said link connecting with an arm 177 which is carried by shaft 69. Disc 174 is also turned in a clockwise direction, viewing Fig. 1, each revolution of the disc producing one complete oscillatory movement of segment gears 158.

The flat surface portion 137 of cam blocks 131 and 132 is provided to prevent raising of the printing frame over an interval sufficient to allow for the movement of the squeegee over the stencil. Although these cam blocks are moving continuously, they do not raise the frame until the inclined surfaces 135 strike the rollers 138, 75 and the drive means for effecting movement of

these blocks is so timed relative to the means for operating the squeegee, hereinafter described, as to insure that the printing frame will be in the lowered position during the interval of movement of the squeegee over the stencil. Also the drive means for operating cam blocks 131 and 132 is accurately timed relative to the conveyor drive means. These two systems of driving gears, both of which have a common source of power through shaft 105, are so arranged that the inclined surface portions of cam blocks 131 and 132 move into engagement with rollers 138 simultaneously with the driving stroke of crank 107 and segment 109 which operate the conveyor chains. Therefore, the printing frame is raised during the interval in which movement is imparted to the conveyor chains and is lowered during the return stroke of crank 107 and segment 109 during which interval the conveyor chains remain stationary.

The clamping means on the gripper bars 61 is also operated in timed relation to the movements of the printing frame and the conveyor chains. The mechanism for operating the gripper clamping means is shown in Figs. 10, 16, and 17. This mechanism is duplicated for the opposite sides of the machine and hence will be described in the singular. In the position of the parts shown in these figures, clamping jaw 81 is in the unclamped position, the arm 84 being out of engagement with latch lever 86. As the gripper bar 95 moves around sprocket 62 and reaches the feed end of the bed plate, the forward end of arm 84 rides over the top edge of a block 177 which is mounted for vertical sliding movement on a bracket 178 which is secured to the inner face of the frame, a sliding T-connection 179 being provided between bracket 178 and block 177 to guide the vertical movement of the latter. Block 177 is thrown upwardly to move arm 84 to clamping position by an arm 181 which is secured on shaft 100 160. The end of arm 181 is provided with a spring-held pawl 182. When shaft 160 is turned 105 in a clockwise direction, viewing Fig. 10, pawl 182 is thrown against the lower edge of block 177, thereby throwing the latter to the dotted line 110 position shown in Fig. 10, during the course of which movement arm 84 is moved sufficiently to bring jaw 81 into clamping engagement with the leading edge of a sheet 183. Arm 84 and jaw 81 are held in this clamped position, represented by 115 the dotted lines in Fig. 10, by latch lever 86 (Fig. 17), the tip 89 of which engages under arm 84. Shaft 160, it will be recalled, is given a movement 120 of oscillation by crank disc 165 so that on the return stroke of arm 181, pawl 182 will pivot on 125 arm 181 and move past the lower end of block 177. Arm 181 is so positioned on shaft 160 that it will effect actuation of block 177 while the printing frame is in lowered position and while 130 the conveyor chains are stationary.

Referring particularly to Figs. 16 and 17, the clamping jaw 81 remains in clamped position until the gripper bar is moved to the rear end of discharge platform 53. A pair of cam blocks 184 are mounted near the rear edge of said platform 140 to effect release of clamping jaw 81 as the gripper bar is about to leave the discharge platform. Each of these blocks is provided along its inner edge with a downwardly projecting channel-shaped bracket 185, the lower edge of which is 145 shaped to provide an upwardly inclined cam surface 186 which is positioned to engage an arm of latch lever 86 as the latter moves past block 184. As the arm of lever 86 rides up on cam surface 186, said lever is pivoted in a counter-clockwise 150

direction, viewing Fig. 17, thereby releasing arm 84 from the tip portion 89 of the lever which drops downwardly and moves jaw 81 to released position. Arms 84 at the opposite ends of shaft 82 being thus released, clamping jaw 81 is sprung upwardly from the sheet by coil springs (not shown) which are positioned in sockets formed in blade 76 and which bear upwardly on metal strips 190 (Fig. 2) carried by shaft 82. A pair 10 of guide fingers 191 (Fig. 16) are positioned on the discharge platform at the opposite sides thereof, and serve to keep the sheet aligned on the platform as it moves to discharging position. These fingers are pivotally secured at one end 15 to the platform, and the other ends thereof are pressed upwardly by coil springs 192 which are contained in openings or wells formed in the platform.

In order to facilitate feeding of the sheets from the feed table into the gripper bars, there is provided between the feed end of the bed plate and the feed table a feed panel 193 (Fig. 2) which is secured to a supporting shaft 180 the latter being journaled at its opposite ends in frame brackets 196. Table 193 is normally positioned horizontally, as shown in Figs. 2 and 9, in which position it forms a continuation of feed table 49. A shaft 195, supported on shaft 180 by a pair of arms 194, is provided with a series of resilient fingers 197 which yieldingly engage the leading edge of the sheet to guide it into the gripper bars. Shaft 180, together with platform 193, is turned on its axis at regular intervals in order to clear the gripper bars as they move into receiving position. For this purpose an arm 198 is secured to shaft 180 in position to be engaged by the end of one of the cam blocks 132 when the latter moves outwardly preliminary to the raising of the printing frame. As the block 132 recedes it allows the shaft 180 and panel 193 to return to the normal position shown in Fig. 2.

Mechanism in addition to the locating arm 122 (Fig. 1) is provided for accurately positioning the gripper bars on the feed bed. It is of great importance that there be provided means for obtaining accurate registration of the sheet with the stencil since for multi-color work it is necessary to have the various colors printed in accurate registration with one another. This locating means includes devices for positioning the gripper bar as it comes to rest at the feed end of the platform and also includes devices for positioning the immediately preceding bar adjacent the discharge end of the bed plate, in which position it holds the sheet during the printing operation. The first of these devices is shown in Figs. 10 and 11. This mechanism is duplicated for each side of the machine and therefore will be described in the singular. It comprises: a locating block 205 which is mounted for vertical movement in a guide channel formed in bracket 178; an actuating arm 206 secured to shaft 160 and provided at its outer end with a cam piece 207 which is pivotally connected at 208 to arm 206; and a latch 209 for holding block 205 in lowered position.

The upper end of block 205 is cradle-shaped, a portion thereof being cut away as indicated at 211 to receive the end lug 79 (Fig. 18) which connects the gripper bar to the conveyor chain. The rear edge of block 205 projects upwardly a considerable distance above the cut-away portion 211 to provide a stop 212 for engaging the edge of lug 79. In the position of the parts shown by the solid lines in Fig. 10, block 205 is in the

raised position and engages lug 79 on the gripper bar to accurately position the latter relative to the feed table. Block 205 is pulled downwardly to the dotted line position shown in Fig. 10 to allow advance movement of the conveyor chains, this movement being effected by the swinging of cam piece 207 to the dotted line position in said figure. In swinging to this position, a flange portion 213 carried by cam piece 207 engages over a stud 214 secured to the lower end of block 205 to pull the latter downwardly. In the backward swing of arm 206, cam piece 207 brushes past roller 214, it being yieldingly connected with arm 206 by a leaf spring 210. This operation is effected in proper timed relation with the movement of the printing frame since arm 206 is operated from shaft 160 which also operates the means for raising and lowering one end of the printing frame. As block 205 moves downwardly it is engaged by an arm 215 of latch 209, the latter being normally urged by a spring (not shown) toward the dotted line position shown in Fig. 11, in which position it seats on the top of a shoulder 216 on block 205 to hold the latter in position which will allow the gripper bar to clear the upper end of said block 205. A coil spring 217 extending between block 205 and the frame, urges said block upwardly against latch arm 215. Latch 209 is thrown to release block 205 as soon as the gripper bar becomes positioned over the latter, this being effected by a cam plate 218 which is secured to a link on the conveyor chain adjacent the gripper bar. As this cam plate approaches the position shown in Fig. 10, it strikes an upwardly projecting arm 219 carried by one arm of lever 209, and as it moves past the projection 219 it pivots lever 209 to the solid line position shown in Fig. 11, thereby releasing block 205 which is immediately pulled upwardly to engage lug 79 on the gripper bar. The incoming gripper bar is thus accurately positioned on the bed and held in such position during the printing operation.

The second of the above-mentioned locating devices, namely, the one which holds the bar accurately in position at the discharge end of the bed plate, is shown in Fig. 9. This mechanism is duplicated for each side of the frame and will be described in the singular. It comprises: a locating bar 221 which is arranged for vertical movement in a mounting block 222, a cam disc 223 fixedly secured to shaft 69; and a lever 224, one end of which is pivotally connected at 225 to block 221, the opposite end of said lever being provided with a roller 226 which engages a cam groove 227 formed in the face of disc 223.

The upper end of block 221 is cut away in the same manner as block 205 which is located at the feed end of the bed plate, the purpose of this being to provide a cradle in the upper end thereof for receiving lug 79 on the end of the gripper bar. In the position of the parts shown in Fig. 9, lug 79 is seated in the upper end of block 221 and the gripper bar, with the sheet secured therein, is thus held in accurate registration with the printing frame and the stencil. Block 221 is raised and lowered in timed sequence with the raising and lowering of the printing frame by the movements of cam segment 223 which, it will be noted, is carried on shaft 69 which, as previously explained, operates the means for raising and lowering one end of the printing frame. As cam segment 223 pivots in a counter-clockwise direction, viewing Fig. 9, roller 226 strikes a raised portion 228 in groove 227 which pivots lever 224 in direction to lower locating block 221. This

operation, which occurs just before the printing frame is lifted, frees the gripper bar from block 221, thereby avoiding interference with the next movement of the conveyor chains.

- 5 The construction and operation of the paint supplying means will now be described, reference being first had to Fig. 12. Stencil 30 is secured to a rectangular wooden frame 229, which is in turn secured by screws 231 to a rectangular metal frame 232. Frame 232 fits into the bottom of the printing frame, the latter being provided with an inwardly extending flange 233 which engages the upper face of frame 232. The stencil frame is removably secured in the printing frame by 10 spring-pressed plungers 234 which project through the sides of the frame into notches 235 formed in frame 232. By pulling outwardly on plungers 234 the stencil frame may readily be released from the printing frame.
- 20 Referring to Figs. 2, 9 and 9a, paint is supplied to stencil 30 from a hopper 236 which is removably secured in one end of the printing frame by means of lugs 237 which project from the end walls of the hopper and which are received in U-shaped 25 sockets 238 formed in brackets 239 which are carried by the side members of the printing frame. The hopper is shaped to provide a storage reservoir 241, the lower end of which is closed by a gate bar 242 which is carried on a shaft 350, the latter being journaled at its opposite ends in brackets 349 which are secured to the walls of the hopper frame. Bar 242, in the closed position shown in Fig. 9a, bears against a stop 351 which is secured to the fountain wall. When bar 242 is turned to 30 open position, paint flows from the reservoir 241 along a curved guide wall 244 and from thence onto the stencil.

Referring particularly to Fig. 9a, means is provided for automatically controlling the opening 40 and closing of gate bar 242 in accordance with the movements of the printing frame. To this end shaft 350 is provided with a pair of spaced brackets 352, the upper ends of which are apertured at 353 to receive bolts 354, the latter being secured in blocks 355 which are carried by the side wall of the hopper 236. Coil springs 356, interposed between brackets 352 and the heads of bolts 354, urge shaft 350 in a counterclockwise direction, viewing Fig. 9a, thus tending to move 45 bar 242 to open position. Fastened to the opposite ends of shafts 350 are a pair of brackets 357, the free ends of which are provided with adjusting screws 358 which are positioned in alignment with bars 359, the latter being secured to the side rails of discharge platform 53. It will 50 be apparent that when the printing frame and hopper 236 are in raised position, springs 356 will move gate bar 242 to open position, thereby allowing paint to flow down onto the stencil. Upon lowering of the printing frame and hopper 55 screws 358 will strike against bars 359, thereby causing brackets 357 to turn shaft 350 and gate bar 242 in a clockwise direction, viewing Fig. 9a, to effect closing of the hopper. The flow of paint onto the stencil is thus automatically regulated by the movements of the printing frame.

Paint which is supplied to the stencil in the manner just described is pressed through the 70 stencil onto the sheets by a squeegee which is arranged to wipe the paint over the stencil to force it through the penetrable areas forming the design to be printed. In accordance with one of the novel features of our invention, the squeegee 75 is arranged to wipe the paint over the stencil

during its advance stroke and then to return paint which has accumulated on the stencil at the end of the advance stroke back to the rear edge of the stencil, from which point it may be wiped over the stencil on the succeeding advance stroke.

Referring to Figs. 12, 13, and 14, the squeegee comprises a trough-shaped back member 245 which is formed from a pair of oppositely inclined side pieces 246 and 247 which ordinarily are formed as a single piece. The lower edge of arm 246 is channeled to receive a rubber wiping element 248, and the lower edge of arm 247 is preferably protected by a strip of rubber 249.

The squeegee is supported in the printing frame by means of stub shafts 251 which extend through rollers 252, the latter in turn resting on flanges 233 which extend along the sides of the frame and serve as guide tracks for said rollers. The ends of shafts 251 carry arms 253 which are provided at their free ends with rollers 254 which engage guide rails 255 projecting inwardly from the sides of the frame. The squeegee is moved back and forth over the stencil by endless conveyor chains 256 which take at one end over idler sprockets 257 and at the other end over drive sprockets 258. The upper run of the chains also takes over a pair of idler sprockets 259. The opposite pairs of sprockets 257 and 259 are carried on stub shafts which project inwardly from the sides of the frame. Drive sprockets 258 are secured on the opposite ends of a drive shaft 261 which is turned in a counter-clockwise direction, viewing Fig. 9, until the squeegee has completed 100 its advance stroke, after which shaft 261 is reversed to return the squeegee to the rear edge of the stencil. The drive means for shaft 261 will be presently described. The squeegee is connected to chains 256 through stub shafts 251 which extend through bearing links 262 connected into the links of said chains.

In Fig. 9 the squeegee is shown in the position which it assumes during its advance stroke. In this position, wiper element 248 is in pressure 105 contact with stencil 30 and rollers 254 carried on the ends of arms 253 are positioned below guide rails 255 so as to hold the wiping element against the stencil. As the squeegee moves to the right it brushes the paint over the stencil, and 110 as it reaches the end of its stroke there is accumulated in front of it a batch of excess paint 263 (Fig. 12). As the squeegee reaches the end of its advance stroke, rollers 254 move to the position shown in Fig. 14 where they strike 115 against the under faces of pivoted cam blocks 264 which normally pivot under their own weight to the dotted line position shown in said figure. As the squeegee completes the end of its stroke, rollers 254 move past blocks 264, whereupon the 120 latter pivot downwardly to the dotted line position shown in Fig. 14. Upon the return stroke 125 of the squeegee, rollers 254 ride up on blocks 264 to assume the position shown by the dotted lines 130 in Fig. 14. The upward swing which is thus imparted to arms 253 at the beginning of the reverse stroke pivots or rocks the squeegee from the position shown by solid lines in Fig. 12 to the position shown by dotted lines in said 135 figure, in which latter position wiping element 248 is held out of contact with the stencil. The squeegee is held in this raised position throughout its return stroke and is again returned to active wiping position when it reaches the end of 140

145 active wiping position when it reaches the end of 140

the return stroke, at which point rollers 254 drop from the rear ends of guide rails 255, thereby dropping wiping element 248 back into engagement with the stencil.

5 In order to prevent accumulation of paint in the forward end of the stencil frame, means is provided for picking up the paint at the forward end of the stencil and returning it to a point from which it may be wiped over the stencil upon the next advance stroke of the squeegee. This means is shown in Figs. 9 and 12 and comprises: a swinging scoop formed from a piece of curved sheet metal 265, and a pair of end plates 266. End plates 266 are secured to back member 245 by means of stub shafts 267 which project through brackets 268, the latter being secured to the ends of back member 245, and said stub shafts 267 being secured at their inner ends to end plates 266. The outer ends of stub shafts 267 are provided with arms 269 which are provided at their ends with rollers 271. Guide rails 272 are supported from the sides of the printing frame by brackets 273 (Fig. 5) and engage rollers 271 to control the position of the scoop supporting arms 269. When the squeegee is in active wiping position, as shown in Fig. 9, rollers 271 engage the under face of guide rails 272 to hold the scoop against the front side 247 of the squeegee. In this position paint which is contained in the 25 scoop may flow therefrom onto the stencil immediately in front of wiping element 248. In other words, in this position the squeegee is arranged to deliver paint contained therein onto the stencil. As the squeegee approaches the end 30 of its stroke the scoop is swung from the position shown in Fig. 9 to the position shown by the solid lines in Fig. 12, this pivotal movement being effected by upwardly inclined guide blocks 270 which engage rollers 271 and cause arms 269 to swing in a clockwise direction, viewing Fig. 12. The scoop is thus swung against the back side 246 of the squeegee and as the latter completes its advance stroke the scoop picks up paint as indicated in Fig. 12. Upon the return stroke the squeegee is pivoted from the position shown by solid lines in Fig. 12 to the position shown by the dotted lines to bring the front side 247 against the scoop. The paint is thus held 35 in the scoop between the curved metal piece 265 and the front side wall 247 of the squeegee. The arms 269 are quite heavy as compared to the weight of the scoop and serve to hold the latter while in the carrying position against the front side 247, this being clearly illustrated by the 40 dotted line position in Fig. 12. The scoop remains in the carrying position throughout the return stroke. At the end of the return stroke the squeegee is pivoted back to the position shown in Fig. 9, as previously explained, and arms 269 cause the scoop to swing with the squeegee. This swinging movement brings rollers 271 below guide rails 272 so that during the advance stroke the scoop is positively held in the delivering position. The squeegee, together with its 45 associated paint pick-up mechanism, will thus operate to wipe paint over the stencil and to return excess paint to a point on the stencil from which it may be again wiped over the stencil until it is finally consumed.

50 The squeegee carrier chains 256 are moved in timed relation to movements of the printing frame and the sheet feed means, the arrangement being such that the squeegee is advanced over the stencil while the printing frame is in lowered position on the bed plate and returned

back to the printing position at the rear edge of the stencil during the interval in which the printing frame is removed from the bed plate. This drive mechanism is shown in Figs. 3 and 4. A crank disc 274 carried on the end of shaft 105 is arranged to have driving connection with said shaft 105 through a latch lever 275 which is pivoted at 276 to the inner face of disc 274. One arm 277 of said lever 275 engages a drive shoulder 278 formed in a collar carried by shaft 105. A bolt 279 carried by arm 277 has sliding engagement with a guide lug 281 carried by disc 274. A coil spring 282, which is confined between lug 281 and lever 277, holds the latter in driving engagement with shaft 105.

80 A segment gear 283 is secured to one arm of a bell-crank 284 which is pivoted at 285 to the frame, the other arm of said crank being slotted, as indicated at 286, to engage an eccentric pin 287 carried by disc 274. Rotation of disc 274 will thus produce oscillatory movement of bell-crank 284 and segment gear 283.

85 Segment gear 283 meshes with a pinion 288 carried on a stub shaft 289. A spur gear 291, which is rigid on shaft 289, drives a stub shaft 100 292 through a spur gear 293. Shaft 292 drives the squeegee chain drive shaft 261 through a bevel gear 294 which meshes with a bevel pinion 295, the latter driving a second bevel pinion 296 through a shaft connection 297. Pinion 296 105 has driving engagement with a bevel pinion 298 carried on the end of shaft 261. Since the oscillatory movements of segment gear 283 are obtained from shaft 105, which also is connected in the gear drive systems for the printing frame 110 actuating mechanism and the conveyor means for the gripper bars, it follows that the squeegee conveyor chains, which are driven from shaft 261, will be operated in timed relation to the movements of the gripper bars and the printing 115 frame. The gear drive between shaft 261 and the oscillating gear 283 is arranged so that the squeegee will be advanced over the stencil while the printing frame is in lowered position and will be carried back to the rear edge of the stencil 120 while the printing frame is in raised position, during which period the gripper bars are moved to bring a fresh sheet into printing position.

125 Since the printing frame is raised and lowered on the bed plate, it is necessary to provide a universal joint connection between bevel pinions 295 and 296 which are disposed on the opposite ends of connecting member 297. To this end said member 297 is formed of two separate shaft portions 299 and 301, each of which is provided 130 with a universal joint connector 302. The provision of these two universal joint connections allows connecting arm 297 to bend when the printing frame is tilted about shaft 39. The portion 301 of member 297 has a plug portion 303 135 which fits into a corresponding socket formed in the portion 299. A longitudinal key connection between this plug and its associated socket allows longitudinal movement between these parts to maintain the driving connection during the 140 movements of the printing frame to and from printing position on the bed plate. The member 297 thus maintains the driving connection to the squeegee chain drive shaft 261 for all positions of the printing frame. The portion 301 of connector member 297 is secured to shaft 292 through a bracket 304 and the portion 299 of said connector is secured to the printing frame through a bearing bracket 305 and a connector arm 306 (Fig. 2).

145

150

A safety device is provided for preventing operation of the machine should an emergency arise, such as failure of the sheet feed means, or the like. To take care of such emergencies, I provide 5 a manually controlled device for checking the downward movement of the printing frame for stopping operation of the squeegee. Referring to Figs. 4, 9, and 15, a throw-out cam 307 is mounted in a guide bracket 308 which is secured 10 to the frame adjacent crank disc 274. When cam 307 is raised from the solid line position shown in Fig. 4, it will engage a roller 309 carried on one arm of latch lever 275 to throw the latter out of driving engagement with shaft 105. The drive 15 to the squeegee chain drive shaft 261 is thus interrupted to stop movement of the squeegee as soon as disc 274 brings roller 309 into engagement with cam 307. Cam 307 is operated from the front of the machine through a hand lever 20 311 (Fig. 1) which is secured to a cross shaft 312, the latter being connected through an arm 313 and a link 314 to one arm of a bellcrank 315 which is pivoted to the bracket which supports cam 307. The other arm of bellcrank 315 connects through 25 a link 316 with cam 307.

The means provided for checking downward movement of the printing frame in the event of an emergency is shown in Figs. 9 and 15. A pair of stop blocks 317 and 318 are secured to resilient 30 arms 319 and 320, respectively, the latter in turn being bolted to a block 321 which is carried by the bed plate frame. A similar pair of stop blocks are mounted on the bed plate frame adjacent the opposite side of the printing frame, one block of 35 the back pair being shown in elevation in Fig. 4. When the blocks are located in the solid line position shown in Fig. 15, the printing frame can not drop fully to printing position, since the blocks engage the sides of the frame to prevent 40 complete downward movement. Normally, however, these blocks are held in the dotted line position shown in Fig. 15, the holding means provided for this purpose consisting of links 322 and 323 which are secured, respectively, to pins 324 and 325 which project downwardly through the bed plate frame. The free ends of links 322 and 323 are provided with upwardly extending pins 326 and 327, respectively, which engage 45 resilient arms 319 and 320. The lower ends of pins 324 and 325 are provided, respectively, with laterally projecting arms 328 and 329 which are adapted to be respectively engaged by the upper ends of arms 331 and 332 (Fig. 9). Arms 331 and 50 332 are secured, respectively, to cross shafts 333 and 334 and the latter are interconnected by a link 335 which is connected at its opposite ends to arms 336 and 337 carried by shafts 333 and 334, respectively. Shaft 334 is connected with the manually controlled shaft 312 through an 55 arm 338, a link 339, and a second arm 341 which is secured to said shaft 312.

Assuming the blocks 317 and 318 are in the dotted line position shown in Fig. 15, movement of hand lever 311 to the right, viewing Fig. 65 1, will move arms 331 and 332 to the left, thereby allowing links 322 and 323 to pivot from the dotted line position shown in Fig. 15 to the solid line position shown in said figure. Both of 70 the blocks 317 and 318 are thus simultaneously thrown under the edge of the printing frame. The blocks at the back side of the frame are operated in similar manner. Moreover, this operation occurs simultaneously with the throw-out of 75 the squeegee drive chain mechanism, since the

latter operation is also effected by the throwing of hand lever 311 to the right, viewing Fig. 1.

The foregoing detailed description has been given for clearness of understanding only, and no unnecessary limitations should be understood therefrom, but the appended claims should be construed as broadly as permissible, in view of the prior art.

What we regard as new and desire to secure by Letters Patent is:

1. In a printing machine, the combination with 80 a bed plate, a printing frame movably supported over the bed plate, and a stencil carried in said frame: of a squeegee mounted in the frame for reciprocation over the stencil; means including an endless carrier chain supported in said frame and reversible drive means therefor for operating the squeegee; means for holding the squeegee in pressure contact with the stencil during the advance stroke; means for lifting the squeegee out of contact with the stencil after completion of the advance stroke; means for holding the squeegee in raised position during the return stroke; and means associated with the squeegee for picking up paint accumulating on the stencil 90 in front of the squeegee at the end of the advance stroke and for returning said paint to a point on the stencil from which it may be wiped over the latter upon the succeeding advance stroke.

2. In a printing machine, the combination with 100 a bed plate, a printing frame movably supported over the bed plate, and a stencil carried in said frame: of a squeegee mounted in the frame for reciprocation over the stencil; means for holding the squeegee in pressure contact with the stencil 110 during the advance stroke; means for lifting the squeegee out of contact with the stencil after completion of the advance stroke; means for holding the squeegee in raised position during the return stroke; and means including a pivoted 115 scoop associated with the squeegee and movable independently of the latter for picking up paint accumulating on the stencil in front of the squeegee at the end of the advance stroke and for returning said paint to a point on the stencil 120 from which it may be wiped over the latter upon the succeeding advance stroke.

3. In a printing machine, the combination with 125 a bed plate, a printing frame movably supported over the bed plate, and a stencil carried in said frame: of a squeegee mounted in the frame for reciprocation over the stencil; means for holding the squeegee in pressure contact with the stencil during the advance stroke; a scoop pivotally supported on the squeegee; means for holding the 130 scoop in position to allow paint to flow therefrom onto the stencil while the squeegee is in wiping position; means operative on approach to the end of the advance stroke to move the scoop from delivering position into position for effecting 135 pick-up of paint accumulating on the stencil in front of the squeegee; means operative at the end of the advance stroke to move the squeegee out of contact with the stencil and to swing the scoop to carrying position; means for holding the 140 squeegee in raised position and the scoop in carrying position during the return stroke; and means operative at the end of the return stroke to return the squeegee to wiping position and the scoop to delivering position, whereby to return paint contained in the scoop to a point on the stencil from which it may be wiped over the latter upon the next advance stroke.

4. In a printing machine, the combination with 145 a bed plate, a printing frame movably supported 150

over the bed plate, and a stencil carried in said frame; of a squeegee mounted in the frame for reciprocation over the stencil; said squeegee including a trough-shaped carriage and a wiping element secured to the back side of said carriage; means for holding the squeegee in position to maintain the wiping element in pressure contact with the stencil during the advance stroke; a scoop pivotally supported on said carriage intermediate the sides thereof; means for holding the scoop in position to allow paint to flow therefrom onto the stencil while the squeegee is in wiping position; means operative upon approach to the end of the advance stroke to move the scoop from said delivering position into position for effecting pick-up of paint accumulating in front of the wiping element; means operative at the end of the advance stroke to rock the squeegee about its support, thereby raising the wiping element from the stencil and moving the front side of the squeegee carriage into paint-retaining position against the side of said scoop; means for holding the squeegee in raised position during the return stroke; and means operative at the end of the return stroke to rock the squeegee back to wiping position and to return the scoop to delivering position, whereby to return paint contained in the scoop to a point on the stencil from which it may be wiped over the latter upon the next advance stroke.

5. In a machine for printing sheet stock and the like: a base, including a bed plate; a printing frame movably supported on the base over the bed plate; a stencil carried in said frame; means for moving the frame vertically relative to the base to carry the stencil to and from printing position on the bed plate; means including an endless conveyor operating in timed sequence with said last-mentioned means for feeding the sheet to be printed onto the bedplate and for removing the printed sheet therefrom; a squeegee mounted for reciprocation in the frame over the stencil; means for holding the squeegee in pressure contact with the stencil during the advance stroke; means for holding the squeegee out of contact with the stencil during the return stroke; and means operating in timed sequence with the movements of the frame for moving the squeegee through its advance stroke while the frame is in lowered position on the bed plate and for moving the squeegee through its return stroke while the frame is away from printing position.

6. In a printing machine: a bed plate; a printing frame movably supported over the bed plate; a stencil carried in said frame; means for raising and lowering the printing frame relative to the bed plate; a squeegee mounted in the frame for reciprocation over the stencil; means for holding the squeegee in pressure contact with the stencil during the advance stroke; means for lifting the squeegee out of contact with the stencil after completion of the advance stroke; means for holding the squeegee in raised position during the return stroke; means operating in timed sequence with the movements of the printing frame for moving the squeegee through the advance stroke while the frame is in printing position on the bed plate and for moving the squeegee through its return stroke while said frame is away from printing position; and means including a pivoted scoop associated with the squeegee and movable independently of the latter for picking up paint accumulating on the stencil in front of the squeegee at the end of the advance stroke and for returning said paint to a point on the stencil

from which it may be wiped over the latter upon the succeeding advance stroke.

7. In a printing machine: a base, including a bed plate; a printing frame movably supported on the base over the bed plate; a stencil carried in said frame; means for moving the frame vertically relative to the base to carry the stencil to and from printing position on the bed plate; a squeegee mounted for reciprocation in the frame over the stencil; means for holding the squeegee in pressure contact with the stencil during the advance stroke; means for holding the squeegee out of contact with the stencil during the return stroke; and drive means operating in timed sequence with the movements of the frame for moving the squeegee through its advance stroke while the frame is in lowered position on the bed plate and for moving the squeegee through its return stroke while the frame is away from printing position, said drive means including an endless conveyor mounted in the printing frame and operatively connected with the squeegee, a motor mounted on the base, and means including a reversing mechanism and a yielding drive connection operatively connecting said motor with said conveyor.

8. In a machine for printing sheet stock and the like: a bed plate; a printing frame movably supported over the bed plate; a stencil carried in the printing frame; means for raising and lowering the printing frame relative to the bed plate; means including an endless conveyor operating in timed sequence with said last-mentioned means for feeding the sheet to be printed onto the bed plate and for removing the printed sheet therefrom; a squeegee mounted in the frame for reciprocation over the stencil; means including an endless carrier chain supported in said frame and reversible drive means therefor for operating the squeegee; means for holding the squeegee in pressure contact with the stencil during the advance stroke; means for lifting the squeegee out of contact with the stencil after completion of the advance stroke; and means for holding the squeegee in raised position during the return stroke.

9. In a machine for printing sheet stock and the like: a bed plate; a printing frame movably supported over the bed plate; a stencil carried in the printing frame; means for raising and lowering the printing frame relative to the bed plate; means operating in timed sequence with said last-mentioned means for feeding the sheet to be printed onto the bed plate and for removing the printed sheet therefrom; a squeegee mounted in the frame for reciprocation over the stencil; means for holding the squeegee in pressure contact with the stencil during the advance stroke; means for lifting the squeegee out of contact with the stencil after completion of the advance stroke; means for holding the squeegee in raised position during the return stroke; means operating in timed sequence with the movements of the printing frame for moving the squeegee through the advance stroke while the frame is in printing position on the bed plate and for moving the squeegee through its return stroke while said frame is away from printing position; and means including a pivoted scoop associated with the squeegee and movable independently of the latter for picking up paint accumulating on the stencil in front of the squeegee at the end of the advance stroke and for returning the same to a point on the stencil from

- which it may be wiped over the latter upon the succeeding advance stroke.
10. In a machine for printing sheet stock and the like: a bed plate; a printing frame arranged for movement vertically to and from printing position relative to the bed plate; a stencil carried in said frame; a squeegee mounted in the frame for reciprocation over the stencil; means including an endless carrier chain supported in 10 said frame and drive means therefor for advancing the squeegee over the stencil when the latter is in printing position, said drive means being operative to carry the squeegee through the return stroke while said frame is away from 15 printing position; and means operating in timed sequence with the movements of the printing frame and the squeegee for feeding the sheets to be printed onto the bed plate and for removing the printed sheets therefrom, said means 20 including an endless conveyor having a series of sheet gripper bars positioned thereon at regularly spaced intervals, said bars being provided with clamping means for engaging and holding the leading edge of the sheet during movement of 25 the latter over the bed plate.
11. In a machine for printing sheet stock and the like: a bed plate; a feed table positioned in alignment with the bed plate adjacent one end thereof; a discharge platform positioned 30 in alignment with the bed plate adjacent the other end thereof; a printing frame movably supported over the bed plate; a stencil carried in said frame; means for moving said frame to and from printing position on the bed plate; 35 a squeegee mounted in the frame for movement over the stencil; means including an endless carrier chain supported in said frame and drive means therefor for advancing the squeegee over the stencil when the latter is in printing position; 40 and means operating in timed sequence with said frame-moving means for feeding the sheets to be printed from said table onto the bed plate and for removing the printed sheets therefrom onto the discharge platform, said means comprising an endless conveyor extending over said bed plate and the discharge platform, and a series of sheet gripper bars arranged on said conveyor at regularly spaced intervals, said bars being provided with clamping means for engaging 45 and holding the leading edge of the sheet during movement of the latter from the feed table over the bed plate and onto the discharge platform.
12. In a machine for printing sheet stock and the like: a bed plate; a feed table positioned in alignment with said bed plate adjacent one end thereof; a discharge platform positioned in 55 alignment with the bed plate adjacent the other end thereof; a printing frame; a stencil carried in said frame; means for moving said frame to and from printing position on the bed plate; a squeegee mounted in the frame for movement over the stencil; means including an endless carrier chain supported in said frame and drive 60 means therefor for advancing the squeegee over the stencil when the latter is in printing position; and means operating in timed sequence with said frame-moving means for feeding the sheets to be printed from said table onto the bed plate and for removing the printed sheets therefrom onto the discharge platform, said means comprising an endless conveyor extending over the bed plate and discharge platform, a series of sheet gripper bars positioned on the carrier at 65 regularly spaced intervals, clamping means on

80 said bars for engaging and holding the leading edge of the sheet, means for throwing said clamping means into clamping position on the sheet after the bar has become positioned on the feed end of the bed plate, and means for holding said clamping means in engagement with the sheet until the latter has moved over the bed plate and onto the discharge platform.

13. In a machine for printing sheet stock and the like: a bed plate; a printing frame arranged for movement to and from printing position relative to the bed plate; a stencil carried in said frame; a squeegee mounted in the frame for reciprocation over the stencil; means for holding the squeegee in pressure contact with the stencil during the advance stroke; means for lifting the squeegee out of contact with the stencil after completion of the advance stroke; means for holding the squeegee in raised position during the return stroke; means for moving the squeegee through the advance stroke while the printing frame is in printing position on the bed plate and for moving the squeegee through its return stroke while the frame is away from printing position and means operating in timed sequence with the movements of the printing frame and the squeegee for feeding the sheets to be printed onto the bed plate and for removing the printed sheets therefrom.

14. In a machine for printing sheet stock and the like: a bed plate; a printing frame arranged for movement to and from printing position relative to the bed plate; a stencil carried in said frame; a squeegee mounted in the frame for reciprocation over the stencil; means for holding the squeegee in pressure contact with the stencil during the advance stroke means for lifting the squeegee out of contact with the stencil after completion of the advance stroke; means for holding the squeegee in raised position during the return stroke; means for moving the squeegee through the advance stroke while the printing frame is in printing position on the bed plate and for moving the squeegee through the return stroke while the frame is away from printing position; means including a pivoted scoop associated with the squeegee and movable independently of the latter for picking up paint accumulating on the stencil in front of the squeegee at the end of the advance stroke and for returning the same to a point on the stencil from which it may be wiped over the latter upon the succeeding advance stroke; and means operating in timed sequence with the movements of the printing frame and the squeegee for feeding the sheets to be printed onto the bed plate and for removing the printed sheets therefrom.

15. In a machine for printing sheet stock and the like: a bed plate; a printing frame arranged for movement to and from printing position relative to the bed plate; a stencil carried in said frame; sheet feed means including an endless conveyor extending over the bed plate and having a series of gripper bars mounted on the conveyor at regularly spaced intervals; means operative while the frame is away from printing position to advance the conveyor a distance sufficient to carry the printed sheet from the bed plate and to feed a fresh sheet thereto; movement-limiting means positioned on the bed plate in the line of travel of said conveyor; and means operating in proper timed relation with the sheet feed means for moving said limiting means into obstructing engagement with the gripper bars as the latter complete their feed movement over the

- bed plate, whereby to bring the conveyor to a rest in a position affording accurate registration of the fresh sheet with the stencil.
16. In a machine for printing sheet stock and the like: a bed plate; a printing frame arranged for movement to and from printing position relative to the bed plate; a stencil carried in said frame; sheet feed means including an endless conveyor extending over the bed plate and having a series of gripper bars mounted on the conveyor at regularly spaced intervals; means operative while the frame is away from printing position to advance the conveyor a distance sufficient to carry the printed sheet from the bed plate and to feed a fresh sheet thereto; movement-limiting means comprising a pair of vertically movable plungers positioned in spaced relation on the bed plate and in the line of movement of the ends of the gripper bars; and means operating in proper timed relation with the feed means for moving said plungers into obstructing engagement with the gripper bars as the latter complete their feed movement over the bed plate, whereby to bring the conveyor to a stop in a position affording accurate registration of the fresh sheet with the stencil. 80
17. In a machine for printing sheet stock and the like: a base, including a bed plate; a stencil; a stencil-supporting frame adapted to be raised and lowered relative to the bed plate; and means for adjusting the position of said frame relative to the base to accommodate the machine to the printing of sheets of various thickness, said adjusting means comprising a series of supporting members movably secured to the frame, and manually operable means for adjusting said members vertically relative to the frame to regulate the lower limiting position of the latter in accordance with the thickness of the sheet to be printed. 85
18. In a machine for printing sheet stock and the like: a base, including a bed plate; a stencil; a stencil-supporting frame adapted to be raised and lowered relative to the bed plate; and means for adjusting the position of said frame relative to the base to accommodate the machine to the printing of sheets of various thicknesses, said adjusting means comprising a series of frame-supporting members mounted at the corners of the frame, a pair of bars extending across the ends of the frame, cam means on said bars for engaging said supporting members, and manually-operable means for moving said bars to change the vertical position of the supporting members relative to the frame, whereby to regulate the lower limiting position of the latter in accordance with the thickness of the sheet to be printed. 90
19. In a printing machine: a base, including a bed plate; a stencil; a stencil supporting frame positioned over the bed plate; rollers mounted on the sides of the frame near the opposite ends thereof; a pair of frame-supporting cam blocks mounted for reciprocation on the base adjacent the opposite sides of the frame near one end thereof, said blocks having cam surfaces for engaging said rollers to raise one end of the frame when the blocks are moved in one direction on the base and for lowering the same when moved in the opposite direction, a second pair of movable cam blocks mounted on the base near the other end of the frame, said last-mentioned blocks being similarly provided with cam surfaces for engaging said rollers to raise the other end of the frame when the blocks are moved in one direction and to low- 95
- er the same when moved in the opposite direction; and means for operating said pairs of blocks in unison to move the frame vertically to and from printing position on the bed plate. 100
20. In a printing machine: a base, including a bed plate; a stencil; a stencil carrying frame movably supported on the base; means providing pivotal and sliding connection between one side of said frame and the base; and means for moving said frames vertically to and from printing position on the base. 105
21. In a printing machine: a base, including a bed plate; a stencil; a stencil carrying frame movably supported over the base; means providing pivotal and sliding connection between one side of said frame and the base; means for moving said frames vertically to and from printing position on the base; and means for tilting the frame about its point of pivotal support on the base. 110
22. In a printing machine: a base, including a bed plate; a printing frame movably supported on the base over the bed plate; a stencil carried in said frame; means for raising and lowering the frame on the base; and stop means operable independently of said last-mentioned means for preventing lowering of the frame to printing position on the base, said stop means comprising stop blocks positioned on the bed plate near the sides thereof, and means including a manually-operated lever for moving said blocks into the path of movement of the printing frame. 115
23. In a printing machine: a base, including a bed plate; a printing frame movably supported on the base over the bed plate; a stencil carried in said frame; means for raising and lowering the frame on the base; a paint storage reservoir supported on said frame adjacent an edge of the stencil; valve means associated with said reservoir for regulating the flow of paint therefrom onto the stencil; and a valve control member arranged to automatically regulate the opening and closing of said valve means in timed sequence with the movements of the printing frame. 120
24. In a printing machine: a bed plate; a printing frame arranged for movement to and from printing position relative to the bed plate; a stencil carried in said frame; a squeegee mounted for movement in the frame over the stencil; means including an endless carrier chain supported in said frame and drive means therefor for advancing the squeegee over the stencil when the latter is in printing position; and stop means independent of said frame-operating means for preventing operation of the squeegee-operating means, said stop means including a throw-out device for disconnecting said drive means from said carrier chain and a manually operated lever operatively connected with said device. 125
25. In a printing machine: a base, including a bed plate; a printing frame movably supported on the base over the bed plate; a stencil carried in said frame; means for raising and lowering the frame on the base; and means for automatically supplying paint to the face of the stencil comprising a storage tank supported on the printing frame, valve means in said tank for regulating the flow of paint therefrom, a control arm associated with said valve means for adjusting the position of the latter, and means supported on the base for contacting said arm upon lowering the printing frame onto the bed plate. 130
